UNITED STATES PATENT OFFICE.

RUSSELL A. TRACE, OF DAYTON, OHIO, ASSIGNOR TO BUCKEYE IRON AND BRASS WORKS, OF DAYTON, OHIO, A CORPORATION OF OHIO.

MACHINE FOR FORMING OIL-CAKES.

1,399,169.

Specification of Letters Patent.

Patented Dec. 6, 1921.

Application filed August 9, 1919. Serial No. 316,368.

To all whom it may concern:

Be it known that I, RUSSELL A. TRACE, a citizen of the United States, residing at Dayton, in the county of Montgomery, and State 5 of Ohio, have invented certain new and useful Improvements in Machines for Forming Oil-Cakes, of which the following is a specification, reference being had therein to the accompanying drawing.

10 This invention relates to machines for forming oil cakes, and has for its particular object to provide an improved construction of an oil cake forming machine of the general type disclosed in my Patent No. 1,302, 15 246, of April 29, 1919.

The principle of construction and operation of machines of this character consists in an arrangement of the cake forming mechanism whereby the hydraulic pressure for 20 operating the machine may be supplied by a comparatively small amount of pressure liquid which is introduced into the pressure cylinders in successive steps, starting with relatively low pressure in the first steps of 25 cake formation and automatically increasing to high pressure for the completion of the operation.

In the present construction, as in the earlier invention referred to, the liquid 30 which is used to operate the machine is supplied under pressure from a pump of any suitable type. To equalize the work of the pump the system includes an accumulator of some well known type into which the 35 liquid is pumped, automatically maintaining the pressure in the accumulator at the state required to operate the cake forming mechanism. Under such a system the advantages 40 of operating with the minimum of pressure liquid are obviously apparent.

To provide an improved pressure cylinder and ram which may be operated with a small amount of liquid is one of the objects of the present invention. This object is realized 45 by constructing the cylinder and ram and their coöperating mechanism so that during the greater part of the forming operation only a comparatively small area of the ram is exposed to the action of the pressure 50 liquid.

During this part of the operation the mold

box which has been charged with the required amount of raw material to form the oil cake is brought up well toward the limit of its movement, the only resistance to this 55 part of the forming operation being the weight of the raw material and the operable parts of the machine and the comparatively slight resistance of the material in the first stages of compression thereof. When the 60 mold box in its upward movement reaches the position where the final forming operation begins the mechanism is automatically adjusted to cause the liquid to exert a much greater pressure on the ram to complete the 65 operation. During the final step of formation the movement is comparatively slight and only a small amount of liquid is required.

To provide for the return or idle stroke of 70 the ram, a reverse valve is provided which may be manually or automatically operated to permit the liquid under pressure of the weight of the descending ram and forming box to flow from the lower portion of the 75 cylinder into the supply tank from which the liquid is pumped into the accumulator. Thus the liquid is kept in sequence of operation and the amount required for continuous 80 operation is kept at the minimum.

In the accompanying drawings:

Figure 1 is a side elevation of an oil cake forming machine embodying my invention with a portion of the valve mechanism taken in cross section;

Fig. 2 is a front elevation of the machine shown in Fig. 1 with a portion thereof consisting of the pressure cylinders and ram taken in cross section;

Fig. 3 is an enlarged detail sectional assembly view of the manually operated controlling valve, together with its operating lever.

As here shown, the forming machine as a whole consists of the main base 1 in which 95 are secured in any suitable manner columns 2—2 and 3 which serve to support the upper forming head 4, the head being supported on a horizontal frame 5 which is secured to the columns in any suitable manner, 100 preferably as here shown.

As shown in Fig. 2, the base 1 is provided

at the central portion thereof with an aperture through which the lower portion of the pressure cylinder 6 extends. The cylinder is supported upon, and may be secured to the base in any suitable manner. The upper portion of the cylinder preferably consists of a detachable extension 7 which serves as a guide to the ram 8 in its up and down movement in the cylinder. Secured to the 10 ram by means of the cross head or platen 9 is the cake forming box 10 which consists of the usual construction and substantially as shown in Figs. 1 and 2 of the drawings.

As shown in the cross section portion of Fig. 2, the ram 8 has between its massive walls a hollow cylindrical portion 11 extending longitudinally therein, and has secured to the lower open end thereof a retaining plate 12 and gasket 13 which constitute a suitable stuffing box between the cylinder 11 and the piston rod 14. The piston rod has secured thereto, preferably integrally, a piston head 15, and, detachably, an annular flange plate 16 which is in effect 25 an extension of the piston head 15 and serves the further purpose of securing to the piston head a suitable piston ring or gasket 17 which acts to form a close fit between the periphery of the piston head and the walls 30 of the cylinder. The piston rod has an aperture 18 extending longitudinally therein, the rod being open to the aperture at its upper end and closed at its lower end. Adjacent its lower end the piston rod is provided with 35 a wide annular channel 19 formed in the periphery thereof, and with oppositely directed passages 20 leading from the annular channel 19 into the longitudinal aperture 18.

The controlling mechanism for the forming mechanism above described consists of an arrangement of automatically controlled valves which are best shown in Figs. 1 and 2 of the drawings.

The pressure liquid is introduced to the mechanism from a suitable accumulator, not shown, through an inlet pipe 22 to a valve of any suitable construction 23, and thence through the pipe 24 to the pressure controlling valve 25 which is a compound valve 50 consisting of a suitable housing 26, having a cylindrical passage 27 extending through substantially the longitudinal center thereof and laterally directed passages 28 and 29 leading from the longitudinal passage 27. The longitudinal passage 27 is occupied by a valve stem 30 which is supported therein by suitable bearings or stuffing boxes 31 and 32 supported in the housing 26. Intermediate its center and lower end the valve stem 30 is 60 provided with a wide annular channel 33 communicating with the passages 28 and 29, respectively, in the operation of the valve.

The upper end of the valve stem 30 has secured thereto, preferably as shown by means of the lock nut 34 a collar 35 which

is connected to the bifurcated end of an arm 36 secured to a pivoted bell crank 37-38 supported in any suitable manner on the extension cylinder 7 and having its arms 37 and 38 alternately movable into the path of a roller 40 secured to the lower end of a suspension bracket 39 carried by the cross head 9, the purpose of which will be explained with the operation of the machine.

The valve 25 has a second valve stem 41, 75 operable in a cylindrical aperture 42 therein. The upper end of the valve stem is supported in a stuffing box bearing 43 and its lower end has secured thereto a valve head 44 coöperating with the discharge end of the passage 28. A passage 45 leads from the aperture 42 into a pipe 46 which is connected by means of a suitable coupling 47 with a pipe 48 communicating with the annular channel 19 of the piston rod 14.

The passage 29 of the valve 25 communicates with a pipe 49 which in turn, through a suitable coupling 50, pipe 51 and passage 52, communicates with the lower portion of the cylinder 6.

The mechanism above described constitutes the intake valves and oil passages whereby the pressure oil is introduced to the cylinders 6 and 11 for operating the ram 8 and forming box 10 in the upward movement thereof, the detailed operation of which will presently be described. The inverse or idle operation of the mechanism is controlled through a valve 53 in which a valve stem 54, as best shown in Fig. 3 of the drawings, is operably supported by a stuffing box bearing 55 and a spring actuated valve head 56, the latter being supported upon a threaded plug 57 secured in the lower portion of the valve housing and having a guide stem 105 and limit stop 58 which serves the double purpose of supporting the compression spring 59 laterally and as a limit stop for the valve stem 54 in the downward movement thereof. The valve is further provided with an 110 inlet port 60, pressure chamber 61, and outlet port 62.

The intake valve 23 is located above, substantially in the same vertical plane with the valve 53, and is of similar construction, 115 consisting of the valve housing 63, valve stem 64, stuffing box 65, valve head 66, supporting plug 67, guide pin 68, compression spring 69, inlet port 70, pressure chamber 71, and outlet port 72. The valve stem 64 is 120 further provided with a wide annular groove 73 formed in the periphery thereof which communicates respectively with the inlet and outlet ports in the operation of the valve.

The valves 23 and 53 are controlled, as 125 here shown, by a manually operated lever 74, which may be pivoted to the frame of the machine in any suitable manner. The lever 74 has contact arms 75 and 76 adapted respectively to actuate the valve stems 54 and 130

64. For automatic operation, the valve lever may be associated with the operable parts of the cake forming mechanism in such a manner that the operation of the valves 23 and 53 will occur in the required sequence to perform the successive steps of the operation.

The operation of the mechanism above described is as follows: The pressure liquid 10 from the accumulator is admitted through pipe 22 and port 70 into valve 23 by operating the lever 74 to raise the valve stem 64 of valve 23, thereby raising valve head 66 and admitting the liquid to enter the pressure 15 chamber 71, from whence it flows through the outlet port 72 into and through pipe 24 into valve 25, the liquid entering the valve through an inlet port 25^a. At this step of the operation the valve mechanism is in the 20 relative positions shown in Fig. 1 of the drawings, the liquid entering the valve immediately adjacent the annular channel 33; thence it moves upwardly under pressure through the passage 28, lifts the valve head 25 44 and flows through pipes 46 and 48 into the annular channel 19 formed in the periphery of the piston rod 14, and through the ports 20 and longitudinal passage 18 into the pressure chamber 11, which is normally 30 filled with the liquid at gravity pressure.

At this stage of the operation the cake forming mechanism is in the relative positions of the parts shown in Fig. 2. It will be understood that the pressure of the liquid 35 against the head of the ram 8 is sufficient to force the ram, together with the forming box 10, upwardly until the roller 40 engages the arm 38 of the bell crank, which controls valve 25, and, by the resulting upward movement of arm 36, raises the valve stem 30 until the upper portion of the annular channel 33 registers with the opening to the passage 29. During this part of the operation the ram 8 and forming box 10 have an upward 45 movement of substantially 8", the piston shaft 14 remaining at rest.

The fluid then flows under pressure through pipes 49 and 51 and the passage 52 into the lower portion 6^a of the cylinder 6. The pressure of the liquid upon the piston head 15, or rather the plate 16 thereof, causes the piston to move with the ram the relatively short distance required, substantially $\frac{3}{4}$ ", to complete the operation, the pressure of the ram being 55 increased during this latter step relatively in the ratio of substantially 7 to 1, being the ratio of pressure surface acted upon by the liquid in the first and second steps of the operation. It will be observed that the total 60 pressure during the entire forming operation is exerted within the cylinder 11 and that the ram 8 is at all times free of direct lifting contact with the piston 15.

During the final step of the forming operation, the pressure of the liquid within

cylinder 11 is much greater than upon the piston plate 16. This results in closing the valve head 44 in the valve 25 by back pressure of the liquid and causes all the direct pressure of the liquid to be exerted upon the 70 piston plate 16.

During the first step of the forming operation, the oil meal in the forming box 10, from which the cake is formed, is brought immediately adjacent, or slightly into compression, with the stationary forming head 4, and during the latter step the meal is compressed to the extent required to form the cake.

To prevent a vacuum or air pressure formation within the cylinder 6, an air duct 77 is provided through the cylinder wall, and to remove any liquid which might accumulate in the lower portion of the cylinder aperture in which the piston shaft 14 operates, a drain port 21 is provided. It will be observed, however, that this aperture never directly receives any of the liquid, and accumulation of liquid therein can result only from seepage around the valve shaft.

To accomplish the idle stroke of the forming mechanism the valve lever 74 is operated in the inverse direction, thereby permitting the valve head 66 of valve 23, under pressure of the spring 69 to close the inlet port 70, 90 thus shutting off the supply of pressure liquid to the cylinder 6. The same movement of the lever serves to actuate the valve stem 54 of the valve 53, thereby lifting the valve head 56 and permitting the liquid to flow by back pressure through pipes 51, 78, 79 and 80 and the inlet port 60 into the valve chamber 61 and thence through the outlet port 62 and suitably arranged piping into the supply tank from which the liquid is pumped into 100 the accumulator.

As shown in Figs. 1 and 2 of the drawings, a check valve 81 may be provided to prevent the liquid under pressure flowing in a direction away from the cylinder and check valves 110 82 and 83 to prevent the liquid under pressure flowing in a direction toward the cylinders. These valves may be of any suitable construction, and may be located as required to provide for proper movement of the 115 liquid.

Having thus fully described my invention, what I claim as new and desire to secure by Letters Patent, is:—

1. In a machine of the character described, the combination, with a ram, a plurality of separate force chambers of different capacity, adapted to co-operate separately and jointly in the operation of said ram, means to conduct liquid to said chambers and to co-operate therewith for the purpose set forth, an inlet valve operable to admit liquid under pressure to one of said chambers whereby the ram will be operated with an initial force, and a valve oper- 130

able to admit liquid to another of said chambers whereby the pressure in said chambers will act jointly in the first chamber to further operate the ram with increased force.

2. In a machine of the character described, the combination, with a ram, a plurality of force chambers of different capacities coöperating in the operation of said ram, means to conduct liquid to said chambers and to coöperate therewith for the purpose set forth, an inlet valve operable manually to admit liquid under pressure to one of said chambers, whereby the ram will be operated through an initial movement, and a valve operable to admit liquid to another of said chambers, whereby the pressure in the first chamber will be intensified and the ram will be further operated with increased force.

3. In a machine of the character described, the combination, with a ram, a plurality of separate force elements of different capacities coöperating in the operation of said ram, means to conduct liquid to said chambers and to coöperate therewith for the purpose set forth, an inlet valve operable to cause liquid under pressure to coöperate with one of said elements to operate the ram with an initial force, said valve being further operable to cause the liquid to coöperate with another of said elements, whereby the force of the first element will be intensified to further actuate the ram.

4. In a machine of the character described, the combination, with a ram, a plurality of separate force elements of different capacities coöperating in the operation of said ram, means to conduct liquid to said chambers and to coöperate therewith for the purpose set forth, an inlet valve operable to cause liquid under pressure to coöperate with one of said elements to operate the ram with an initial force, said valve being further operable to cause the liquid to coöperate with another of said elements, whereby the liquid will act upon said elements jointly to intensify the force of the first element to further actuate the ram.

5. In a machine of the character described, the combination, with a ram, a plurality of separate force chambers of different capacities adapted to coöperate separately and jointly in the operation of said ram, means to conduct liquid to said chambers and to coöperate therewith for the purpose set forth, an inlet valve operable to admit liquid under pressure to one of said chambers, whereby the ram will be operated with an initial force, and means to further operate said valve whereby the liquid will be admitted to another of said chambers and will act upon the liquid in the first

named chamber to further operate the ram with increased force.

6. In a machine of the character described, the combination, with a ram, a plurality of separate force elements having areas of predetermined ratio, means operable to cause liquid under pressure to coöperate with one of said elements to actuate the ram with an initial force; said means being further operable to cause the liquid to coöperate with said elements jointly to intensify the action of one of said elements to further operate the ram with force increased in said ratio.

7. In a machine of the character described, the combination, with a ram, a plurality of separate force elements having areas of predetermined ratio, means operable to cause liquid under pressure to coöperate with one of said elements to actuate the ram with an initial force; said means being further operable automatically to cause the liquid to coöperate with said elements jointly to further actuate the ram, whereby the force exerted thereon by the first-named element will be increased in said ratio.

8. In a machine of the character described, the combination, with a ram, a plurality of force chambers adapted to coöperate in the operation of said ram, an inlet valve operable to admit liquid under pressure to one of said chambers whereby the ram will be actuated with an initial force, a piston coöoperating with said chambers, means to further operate said valve whereby the liquid will be admitted to another chamber and the piston will be actuated thereby to cause operation of the ram with increased force.

9. In a machine of the character described, the combination, with a ram, a plurality of force chambers adapted to coöperate in the operation of said ram, an inlet valve operable to admit liquid under pressure to one of said chambers whereby the ram will be actuated with an initial force, a piston coöoperating with said chambers and normally at rest during said initial operation, and means to further operate said valve whereby the liquid will be admitted to another chamber and the piston will be actuated thereby to cause operation of the ram with increased force.

10. In a machine of the character described, the combination, with a ram, a plurality of force chambers adapted to coöperate in the operation of said ram, an inlet valve operable to admit liquid under pressure to one of said chambers whereby the ram will be actuated with an initial force, a piston coöoperating with said chambers having means to conduct said liquid therethrough into said chamber; and means

- to further operate said valve whereby the liquid will be admitted to another chamber and the piston will be actuated thereby to cause operation of the ram with increased force.
11. In a machine of the character described, the combination, with a ram, a plurality of force chambers adapted to co-operate in the operation of said ram, an inlet valve operable to admit liquid under pressure to one of said chambers whereby the ram will be actuated with an initial force, a piston operable in said chambers, and means to further operate said valve whereby the liquid will be admitted to another chamber and the piston will be actuated thereby to cause operation of the ram with increased force.
12. In a machine of the character described, the combination, with a ram, a plurality of force chambers adapted to co-operate in the operation of said ram, an inlet valve operable to admit liquid under pressure to one of said chambers whereby the ram will be actuated with an initial force, a piston operable in one of said chambers and having an apertured piston shaft whereby the liquid is conducted into the other of said chambers, and means to further operate said valve whereby the liquid will be admitted to another chamber and the piston will be actuated thereby to cause operation of the ram with increased force.
13. In a machine of the character described, the combination, with a ram, a plurality of force chambers adapted to co-operate in the operation of said ram, an inlet valve operable to admit liquid under pressure to one of said chambers whereby the ram will be actuated with an initial force, a piston operable in one of said chambers having annular and longitudinal passages therein whereby the liquid from said valve is conducted to the other of said chambers, and means to further operate said valve whereby the liquid will actuate the piston and cause the ram to operate with increased force.
14. In a machine of the character described, the combination, with a ram, a plurality of force chambers adapted to co-operate in the operation of said ram, an inlet valve operable to admit liquid under pressure to one of said chambers whereby the ram will be actuated with an initial force, a piston operable in one of said chambers, and a hollow piston shaft having one of its ends extending into the other chamber and its opposite end co-operating with passages leading from said valve whereby the liquid is conducted to said last-named chamber, and means to further operate said valve whereby the liquid will actuate the piston and cause the ram to operate with increased force.
15. In a machine of the character described, the combination, with a ram, a plurality of force chambers adapted to co-operate in the operation of said ram, an inlet valve operable to admit liquid under pressure to one of said chambers whereby the ram will be actuated with an initial force, a piston operable in one of said chambers and a hollow piston shaft having one of its ends extending into the other chamber and its opposite end co-operating with passages leading from said valve whereby the liquid is conducted to said last-named chamber and excluded from the other chamber, and means to further operate said valve whereby the liquid will actuate the piston and cause the same to operate with increased force.
16. In a machine of the character described, the combination, with a ram, a plurality of force chambers adapted to co-operate in the operation of said ram, one of said chambers being normally filled with liquid, an inlet valve operable to admit liquid under pressure to said chamber whereby the ram will be actuated with an initial force, a piston co-operating with said chambers, and means to further operate said valve whereby the liquid will actuate the piston and cause the same to operate with increased force.
17. In a machine of the character described, the combination, with a ram, a plurality of force chambers co-operating in the operation of said ram, means to conduct liquid to said chambers and to co-operate therewith for the purpose set forth, an inlet valve operable to admit liquid under pressure to one of said chambers through liquid passages leading thereto from said valve, whereby the ram will be actuated by an initial force, means to further actuate the valve whereby said passages will be automatically closed and the liquid will be conducted through other passages to the other of said chambers and the ram will be actuated with increased force.
18. In a machine of the character described, the combination, with a ram, a plurality of force chambers co-operating in the operation of said ram, means to conduct liquid to said chambers and to co-operate therewith for the purpose set forth, an inlet valve operable to admit liquid under pressure to one of said chambers whereby the ram will be actuated in an initial movement, means operable by the ram in said movement to actuate said valve to admit the liquid into the other chamber and a check valve whereby delivery of liquid to the first chamber will be automatically stopped and the ram will be actuated in a further movement.
19. In a machine of the character described, the combination with a ram, a plurality of force chambers co-operating in the operation of said ram, means to conduct

liquid to said chambers and to coöperate therewith for the purpose set forth, an inlet valve manually operable to admit liquid under pressure to one of said chambers whereby 5 the ram will be actuated by an initial movement, a second valve, a pivoted lever automatically operated by the ram in said movement to actuate said valve to admit the liquid into the other chamber whereby the ram 10 will be further actuated, said lever being actuated on the return stroke of the ram to restore the valve to normal relation and an outer valve manually operable at the end of the ram movement whereby the liquid may 15 be discharged from said chambers.

20. In a machine of the character described, the combination, with a ram, a plu-

rality of force chambers of different capacities coöperating in the operation of said ram, means to conduct liquid to said chambers 20 and to coöperate therewith for the purpose set forth, an inlet valve operable manually to admit liquid under pressure to one of said chambers whereby the ram will be operated through an initial movement, and a valve 25 operable automatically to admit liquid to another of said chambers whereby the ram will be further operated with increased force, and an outlet valve manually operable at the end of the ram movement whereby 30 the liquid may be discharged from said chambers.

In testimony whereof I affix my signature.
RUSSELL A. TRACE.
